MECHANICAL PENCIL

Joseph F. Kupczyk, Chicago, Ill.

Application September 3, 1943, Serial No. 501,077

11 Claims. (Cl. 120—17)

The present invention relates to mechanical pencils and has for its main object the provision of improved mechanism for ejecting lead.

A still further object of the present invention is the provision of an improved collet mechanism in a mechanical pencil for alternately clamping and releasing lead for the purpose of successively shifting the same.

With the above general objects in view and others that will appear as the invention is better understood, the same consists in the novel construction, combination and arrangement of parts hereinafter more fully described and illustrated in the accompanying drawing and pointed out in the appended claims.

In the drawing forming a part of this application, and in which the same designating characters refer to the same parts throughout the several views;

Fig. 1 is a longitudinal cross-sectional view through the mechanical pencil, illustrating the mechanism thereof while in an inoperative position;

Fig. 2 is a similar view, illustrating the mechanism at the initial stage of its actuation, conditioned to receive lead;

Fig. 3 is a similar view, showing the condition of the mechanism during the stage of its complete actuation; and

Fig. 4 is a transverse cross-sectional view through the mechanical pencil taken on line 4—4 of Fig. 1.

Referring in detail to the present drawing there is shown barrel 10, within the rear end of which a shorter cylinder 11 is received for longitudinal sliding movement therein. The outer end of said cylinder 11 is adapted to receive in a frictional engagement the reduced end 12 of cap 13. Receivable in a frictional engagement within said cylinder 11 and within its inner end is plug 14. The space within said cylinder 11, defined by said cap 13 and plug 14, constitutes magazine 15, for receiving therewithin a supply of leads 16.

At the rear face of said plug 14 a concentric and an outwardly flaring depression 17 is made, for facilitating sliding of the adjacent ends of leads 16 to bore 18, made centrally and longitudinally of said plug 14. At the opposite face of said plug 14 a tapering cavity 19 is made, which by its upper constricted end communicates with said bore 18.

The invention further includes stopper 20 frictionally held within the lower end of barrel 10. Projecting from the lower end of said stopper 20 is a reduced extension 21, with the resultant shoulder 22 which abuts and rests upon shoulder 23 made in the plastic cover or sheath 24, which envelops said barrel 10 and extension 21. By virtue of this arrangement barrel 10,

stopper 20, extension 21 and sheath 24 are in a mutually stationary condition.

Made centrally of said stopper 20 is bore 25, which, towards the lower end of said stopper 20 is enlarged and tapering as at 26 and communicates with a bore 27 made in said extension 21. The lowermost end of said bore 27 is threaded as at 28 to receive in threaded engagement the reduced boss 29 of tip 30.

10 The invention further includes a longitudinal collet 31 provided with a central bore which is in alignment with bore 18 to receive leads 16. The lower end of said collet 31 has an outwardly flaring head 32, which normally remains in engagement with the tapering bore 26 made in said stopper 20 as aforesaid. The upper end of said collet 31 is reduced in thickness to affect head 33, which has a downwardly tapering face 34 and an upwardly tapering face 35 at its extreme termination, which conforms to the form of cavity 19. Both the upper and lower ends of said collet 31 are longitudinally slit as at 36, with the resultant tines tending to flare outwardly of the axis of the said collet 31 so as to permit free and unimpeded sliding motion for lead 16 as they are permitted to slide within the bore made in said collet 31 and to constrict the bore with an exerted clamping action upon the lead when the ends of said collet 31 are compressed as will be hereinafter seen.

20 Positioned within barrel 10 for free sliding movement and adjacent the lower end of cylinder 11 and plug 14 is a split ring 37 within which the upper end of collet 31 is received. The aperture in said ring is downwardly tapering as at 38 for engaging the downwardly tapering face of head 33. Interposed between said ring 37 and stopper 20 is coil spring 39.

25 It is observed that bore 25 made in stopper 20 is of a larger diameter than head 33 to permit assembly of said collet within the mechanical pencil through the lower end of extension 21. Upon insertion of said collet therethrough ring 37 is placed upon the reduced end thereof through

30 its transverse slit.

35 Receivable within bore 27, and resting upon the upper end of boss 29 is a round tray 40, the annular side wall of which at its inner face is outwardly flaring as at 41. Said tray at its bottom wall is apertured on line with the central bore in collet 31 and bore 42 made in tip 30. Resting upon the upper termination of side wall of said tray 40 is a compression ring 43.

40 Placed within bore 42 in tip 30 is a friction tube 44 which engages leads 16 and prevents their dropping out of tip 30, permitting however sliding movement thereof under ejecting action of collet 31 as will be hereinafter apparent. Tube 44 made of sheet brass, having a bore of a diameter corresponding to the diameter of leads, will

assure sufficient degree of friction between the tube and the leads.

In normal position of the mechanism of the pencil spring 39, bearing against ring 37 maintains the latter in contact with the downwardly tapering face 34 of head 33, maintaining cylinder 11 in its elevated inoperative position as is seen in Fig. 1. The engagement of ring 37 with head 33 compresses the tines of collet 31 at the upper end thereof, preventing any leads from being received within the bore of collet 31. This action of spring 39 likewise maintains the lower end of collet 31 locked due to the engagement of head 32 with the tapering bore 26. In this position no leads may freely pass through bore in collet 31, but any lead remaining within said bore is clamped due to the clamping action of head 33 or the other end of collet 31. Lead which is within tip 30, bearing against the adjacent lead which remains within collet 31 will be prevented from making any backward sliding movement into the pencil.

Upon applying manual pressure upon cap 13, the initial or first stage of the operation of the pencil is brought about, namely downward sliding of cylinder 11 within barrel 10. This compresses spring 39 and slides ring 37 downwardly and out of engagement with head 33. Disengagement of ring 37 from head 33 permits the upper end of collet 31 to open and to receive a lead which falls thereto through bore 18. This initial operation has for its object the passage of a lead through the upper end of collet 31, the wall of tapering cavity 19 remaining out of contact with the adjacent tapering face 35 of head 33 as is clearly seen in Fig. 2. By this operation the lower end of collet 31 remains unaffected, the same still remaining in engagement with stopper 20 through its outwardly flaring head 32.

When cylinder 11 is further shifted due to the exertion of manual pressure upon cap 13, the next stage of the operation takes place, as shown in Fig. 3, namely, plug 14 is shifted downwardly so as to engage its tapering cavity 19 with the tapering face 35 of head 33, which results in closing of the several tines of the upper end of collet 31, bringing about a clamping action upon the lead remaining within the said upper end of collet 31. This operation shifts collet 31 downwardly due to the pressure of plug 14 at the upper end thereof, shifting the lower end of collet 31 and out of engagement with the tapering bore 26 so as to permit opening of the several tines at the lower end of collet 31. The downward shifting of collet 31, and the resultant bearing upon ring 43 compresses said ring due to the action of the tapering face 41 of tray 40. This downward shifting of collet 31 has for its object to close the upper end of said collet and to simultaneously open the lower end thereof, so as to permit any lead remaining within the lower end of said collet to shift downwardly through bore in tray 40 and into bore 42 in tip 30.

If there are three leads within the several bores, as seen in Fig. 3, the uppermost remaining within upper end of collet 31 is clamped therewithin, while lead within the lowermost end of collet 31 is susceptible of free shifting movement within said collet, while the lowermost lead within tip 30 likewise is subject to free shifting movement, subject only to the friction action of tube 44. When the pressure at cap 13 is released, collet 31 springs back due to the action of spring 39 and its pressure on ring 37. The latter bearing against head 33, shifts said collet back to its

inoperative position, shown in Fig. 1. When in that position both ends of collet 31 exert a strong clamping action upon the leads remaining therewithin.

5 To bring a lead within tip 30 for writing condition a number of alternate pressures and releases at cap 13 may be required particularly at the time when no leads remain within the several bores centrally of the pencil. When however, at least 10 three leads have been brought within the central bores of the pencil, conditioning of the lowermost lead for its writing position may require only one or two alternate pressures or releases at cap 13.

From the hereinabove description it will be 15 seen that by exerting alternate pressures and releases at cap 13, alternate opening and clamping of the lower end and upper end of collet 31 is brought about for the purpose of downward shifting of any leads within collet 31.

20 It is further observed that the uppermost lead 16 within the upper end of collet 31 shifts downwardly within said collet by virtue of its gravity when collet 31 is brought to the initial position illustrated in Fig. 2. When the upper end of 25 collet 31 is clamped, as in the position shown in Fig. 3, the lead exerting pressure upon the adjacent lead within the lower end of collet 31 shifts the latter when the lower end of collet 31 is opened as seen in Fig. 3, while said latter lead 30 shifts the lowermost lead in tip 30.

It is further observed that during the application of pressure upon cap 13 opening of the upper end of collet 31 is effected for a short interval of space to receive lead 16, or to permit further 35 shifting movement of said lead 16 within collet 31. Further application of pressure clamps the upper end of collet 31 and shifts said collet downwardly to open the lower end thereof, so that any lead remaining within the lower end of collet may 40 shift downwardly due to its gravity. Upon the release of pressure upon cap 13 collet 31 retracts to its original inoperative position, and while shifting upwardly both ends of collet for an interval of space remaining open, the upper end 45 thereof by virtue of the fact that spring 39, bearing against ring 37 shifts the latter into an ultimate engagement with the outwardly tapering wall 38 of head 33, and until that shifting movement of ring 37 has been completed the upper end 50 of collet 31 remains open. Likewise head 32 at the lower end of collet 31 remains open, because the same is out of engagement with the tapering bore 26, until said head ultimately comes into engagement therewith. While collet 31 shifts upwardly with its both ends open, any leads remaining therewithin will be unaffected by the upward shifting movement of said collet 31. They will remain in the position in which they were prior to the upward shifting movement of collet 31 by virtue of their gravity. The object of ring 55 43 is to maintain said ring in contact with the lower end of collet 31, and thereby to maintain the downward tapering face 35 of head 33 in contact with the tapering wall of cavity 19, during the downward shifting movement of collet 31, after the several parts of the mechanism have passed the initial stage shown in Fig. 2, for the purpose of keeping the upper end of collet 31 in a clamped position so as to bear against the lower leads within the lower end of collet 31 and in tip 30 for sliding the same forwardly of the pencil. As collet 31 shifts downwardly, and as it comes in contact with said compression ring 43, further bearing of the lower end of collet 31 upon said ring compresses the same and forces it into tray 60 65 70 75 76

40 to slide to the bottom thereof while guided by the downwardly tapering face 41 of the side wall of the said tray 40. When collet 31 retracts upon the release of the pressure upon cap 13, said ring 43 has no function insofar as mechanism of the pencil is concerned, except that it springs back to its original inoperative position shown in Figs. 1 and 2.

Thus it will be seen that when the mechanism of the pencil is in the position illustrated in Fig. 3, lead 16 within the upper end of collet 31 is clamped and firmly held therewithin against sliding movement. The lower end of collet 31, however, is then completely opened, so that when the pressure upon cap 13 is released and collet 31 retracts, lead 16 within the lower end of collet will not be retracted, due to the fact that there is no frictional hold therebetween, and the lead will remain in its extended position, due to gravitational force, as well as due to its frictional engagement with tube 44. When the action at cap 13 is repeated all the leads remaining within bores 18, 42 and the bore in collet 31 will be successively shifted towards the front of the pencil.

From the hereinabove description it will be seen that in effect heads 32 and 33 provide two longitudinally disposed and cooperating clutches, by virtue of which arrangement leads remaining within said heads, collet 31 and tip 30 will not slide back into the pencil when excess pressure is applied at the lowermost lead during writing operation.

While there is described herein a preferred embodiment of the present invention, it is nevertheless to be understood that minor changes may be made therein without departing from the spirit and scope of the invention as claimed.

What I claim as new is:

1. A mechanical pencil comprising a barrel, a stopper in the front end of said barrel, said stopper being provided with a central inwardly tapering bore, a collet, one end of said collet being slit to effect a plurality of tines, said collet being provided with a central bore to receive leads therewithin, the said slit end of said collet being outwardly flaring for the purpose of engaging the said end of collet with the periphery of said bore in said stopper for the purpose of compressing said tines towards the longitudinal axis of said collet for the purpose of clamping the lead within said collet, a tip in engagement with said stopper, said tip being provided with a longitudinal bore in alignment with the bore in said collet, means for normally maintaining said tines in engagement with the periphery of said bore, means for longitudinally shifting said collet for the purpose of bringing said tines out of engagement with the periphery of said bore for releasing the lead within the collet, means in said tip for engaging leads fed thereto from said collet, and means within the rear end of said collet for pressing against the lead remaining within the front end of the collet when said tines remain open for shifting the lead into said bore in said tip when the collet shifts towards the front end of the pencil.

2. A mechanical pencil comprising a barrel, a collet therewithin, said collet having a bore to receive a number of leads in an end to end position, each end of said collet being slit to define a plurality of tines, means at each end of the collet engaging said tines for maintaining them in a position compressed towards the longitudinal axis of the collet for clamping the leads remaining within said bore, a tip in engagement with the

front end of the pencil, said tip being provided with a longitudinal bore in alignment with said bore in said collet, means for shifting said collet to or away from said tip, means for rendering said first named means inoperative on operation of said second named means for successively releasing and shifting leads within said collet and into said bore within said tip, and means within said tip for frictionally engaging the leads shifting into its bore.

3. In a mechanical pencil a barrel, a collet therewithin, said collet being provided with a longitudinal bore to receive leads in an end to end position, a clutch at each end of said collet for normally clamping the leads in said collet for preventing the longitudinal shifting movement thereof, means for longitudinally shifting said collet in said barrel, means for opening the clutch at the rear end of the collet preceding the shifting of the latter for receiving a lead within the rear end of the collet, and means for opening the clutch at the front end of the collet and for simultaneously closing the clutch at the rear end of the collet as the shifting movement of the collet commences on operation of said first named means for releasing the lead remaining within the front end of the collet.

4. In a mechanical pencil, a barrel, a collet therewithin, said collet being provided with a longitudinal bore to receive leads in an end to end position, a clutch at the front end of said collet, a clutch at the rear end of said collet, means for normally maintaining said clutches in a locked engagement with leads remaining in said collet, means for shifting said collet longitudinally of said barrel, means for opening the clutch at the rear end of the collet preceding its shifting movement for receiving a lead through the rear end thereof, and means for rendering said last named means inoperative for locking the clutch at the rear end of the collet and for simultaneously opening the clutch at the front end of the collet on operation of said first named means for releasing the lead at the front end of the collet.

5. In a mechanical pencil, a barrel, a collet therewithin, said collet being provided with a longitudinal bore to receive leads in an end to end position, a clutch at the front end of said collet, a clutch at the rear end of said collet, means for normally maintaining said clutches in a locked engagement with leads remaining in said collet, means for shifting said collet longitudinally of said barrel, means for opening the clutch at the rear end of the collet preceding its shifting movement for receiving a lead through the rear end thereof, means for rendering said last named means inoperative for locking the clutch at the rear end of the collet and for simultaneously opening the clutch at the front end of the collet on operation of said second named means for releasing the lead at the front end of the collet, and means for retracting said collet to its normal position.

6. In a mechanical pencil, a barrel, a collet therewithin, said collet being provided with a longitudinal bore to receive leads in an end to end position, a clutch at the front end of said collet, a clutch at the rear end of said collet, means for normally maintaining said clutches in a locked engagement with leads remaining in said collet, means for shifting said collet longitudinally of said barrel, means for opening the clutch at the rear end of the collet preceding its shifting movement for receiving a lead through the rear

end thereof, means for rendering said last named means inoperative for locking the clutch at the rear end of the collet and for simultaneously opening the clutch at the front end of the collet on operation of said second named means for releasing the lead at the front end of the collet, a tip in a rigid engagement with the front end of said barrel, said tip being provided with a bore in alignment with the bore in said collet, the lead released at and through the front end of said collet being adapted to enter said bore in said tip, and means in said tip for gripping the lead which has entered said latter bore from said collet.

7. In a mechanical pencil, a barrel, a collet 15 therewithin, said collet being provided with a longitudinal bore to receive leads in an end to end position, a clutch at the front end of said collet, a clutch at the rear end of said collet, means for normally maintaining said clutches in a locked engagement with leads remaining in said collet, means for shifting said collet longitudinally of said barrel, means for opening the clutch at the rear end of the collet preceding its shifting movement for receiving a lead through the rear end thereof, means for rendering said last named means inoperative for locking the clutch at the rear end of the collet and for simultaneously opening the clutch at the front end of the collet on operation of said second named means for releasing the lead at the front end of the collet, means for retracting said collet to its normal position, a tip in a rigid engagement with the front end of said barrel, said tip being provided with a bore in alignment with the bore in said collet, the lead released at and through the front end of said collet being adapted to enter said bore in said tip, and means in said tip for gripping the lead entering said latter bore from said collet for preventing retraction thereof during the retracting movement of said collet.

8. In a mechanical pencil, a barrel, a collet therewithin, said collet being provided with a longitudinal bore to receive leads in an end to end position, a clutch at the front end of said collet, a clutch at the rear end of said collet, means for normally maintaining said clutches in a locked engagement with leads remaining in said collet, means for shifting said collet longitudinally of said barrel, means for opening the clutch at the rear end of the collet preceding its shifting movement for receiving a lead through the rear end thereof, means for rendering said last named means inoperative for locking the clutch at the rear end of the collet and for simultaneously opening the clutch at the front end of the collet on operation of said second named means for releasing the lead at the front end of the collet, means for retracting said collet to its normal position, a tip in a rigid engagement with the front end of said barrel, said tip being provided with a bore in alignment with the bore in said collet, the lead released at and through the front end of said collet being adapted to be pushed into said bore in said tip by the adjacent lead in said collet remaining immediately rearwardly thereof, and means in said tip for frictionally engaging the lead entering said latter bore from said collet for preventing shifting thereof in either direction when said collet remains in a normal retracted position.

9. In a mechanical pencil, a barrel, a collet

therewithin, said collet being provided with a longitudinal bore to receive leads in an end to end position, a clutch at the front end of said collet, a clutch at the rear end thereof, means for normally maintaining both of said clutches in a locked engagement with leads remaining in said collet, means for intermittently shifting said collet forwardly and rearwardly in a longitudinal direction with respect to said barrel, means for opening and closing both of said clutches on shifting of said collet for successively shifting all of the leads remaining in said collet and into a forward direction, and means associated with the front end of said barrel for engaging the front-most lead as it successively shifts out of the front end of said collet for preventing shifting thereof in either direction when said collet shifts rearwardly.

10. A mechanical pencil comprising a barrel, a collet within said barrel and in longitudinal relation therewith, both ends of said collet being longitudinally slit to effect clamping tines, said collet being provided with a bore centrally and longitudinally thereof to successively receive leads, a tip rigidly carried by the front end of said barrel, said tip being provided with a longitudinal bore in alignment with the bore in said collet, means to actuate said collet for shifting the same towards said tip, means for normally maintaining said tines at both ends of said collet in a clamping, closed position when said collet is in a retracted position for rigidly engaging leads remaining within said collet, means for rendering said second named means inoperative for opening the tines at the rear end of the collet preceding the operation of said first named means for permitting the collet to receive a lead through the rear end thereof, and means for closing the tines at the rear end of the collet and for simultaneously opening the tines at the front end thereof on operation of said first named means for releasing the lead at the front end of the collet and for shifting the same into the bore of said tip, and means in said tip for preventing lead remaining therewithin from shifting with the collet when the same retracts into its normal position.

11. In a mechanical pencil a barrel, a collet therewithin, said collet being provided with a longitudinal bore to receive leads in an end to end position and with an enlargement at one end thereof for defining a tapering head, said head being transversely slit longitudinally of said collet for providing a plurality of outwardly tapering tines, a stopper in rigid association with said barrel, said stopper having a central opening through which the opposite end of said collet extends, means in said stopper permitting forward shifting movement of said collet therewithin but preventing rearward movement thereof, a ring surrounding said collet and normally in engagement with the outer faces of said outwardly tapering tines for clamping lead remaining within said collet, a coil spring interposed between said stopper and said ring for normally maintaining said ring in engagement with said tines, and means for shifting said ring against said coil spring for disengaging the same from said tines for releasing the lead clamped therewithin, the released lead being adapted to shift through the opposite end of said collet.
